UNITED STATES PATENT OFFICE.

ERASTUS E. WINKLEY, OF LYNN, MASSACHUSETTS, ASSIGNOR TO UNITED SHOE MACHINERY CORPORATION, OF PATERSON, NEW JERSEY, A CORPORATION OF NEW JERSEY.

METHOD OF MAKING BOOTS AND SHOES.

Application filed January 25, 1918, Serial No. 213,683. Renewed November 21, 1922.

To all whom it may concern:

Be it known that I, ERASTUS E. WINKLEY, a citizen of the United States, residing at Lynn, in the county of Essex and State of Massachusetts, have invented certain new and useful Improvements in Methods of Making Boots and Shoes; and I do hereby declare the following to be a full, clear, and exact description of the invention, such as will enable others skilled in the art to which it appertains to make and use the same.

This invention relates to methods of making boots and shoes, and it has special reference to such methods as are adapted for the production of regular and well-shaped boots and shoes, particularly at the heel end thereof.

In the commercial manufacture of boots and shoes, it has heretofore been customary to attach a rough heel to the heel-seat portion of the outsole, after which a definitely shaped, condensed top-lift is spanked on. The heel end of the shoe, constituting the rough heel and the heel seat of the outsole, is then trimmed or shaved to its final size and form by means of a cutter, the movements of which are prescribed and determined through the agency of guide members that cooperatively engage the edge of the top-lift and crease of the heel-seat between the upper and the outsole. The final shape of the heel end, therefore, depends upon the accuracy of the position of the top-lift and the size and contour of the top-lift and heel crease. The heel crease is rarely perfectly regular but is generally distorted and somewhat uneven, and is practically always affected by the back seam of the shoe. Moreover, the top-lift is very apt to be located slightly off centre.

The result of trimming the heel end of the shoe to the top-lift and heel crease as guides, therefore, is to produce nonuniform shoes, the heel ends of which are more or less irregular, distorted and lop-sided in shape.

The object of the present invention is to provide a method of finishing the heel ends of boots and shoes, the practice of which results in regularity, uniformity and substantial perfection in size, form and appearance.

In accordance with the present invention, it is proposed to employ heels that, before attachment to the shoe, are made to definite,

regular and final size and shape, preferably, although not necessarily, as set forth in a copending application Serial No. 213,681 filed by the present applicant of even date herewith. The heel is accurately positioned with respect to the shoe itself and may even, if desired, be attached to the heel-seat of the outsole, after which the unfinished heel-seat of the outsole is fitted, as by being trimmed or trimmed and randed, to the definitely shaped heel. This is accomplished by means of a suitable cutter, the quantity of waste stock to be removed being gaged, or determined, by a controlling device that co-operatively engages the lateral surface of the heel body contiguous to the seat face of the heel. The edge of the heel-seat and the heel may be, in some kinds of shoes, later scoured and finally finished together in accordance with customary practice.

The novel method will be most readily understood by a reference to the accompanying drawing illustrating the preferred manner of practising the invention.

In the accompanying drawing the single figure is a view, in side elevation, of a shoe, having a heel of final size and shape attached, properly supported for performing the finishing operations on its heel end in accordance with the present method.

The mechanism illustrated and described as being adapted for use in practicing the method of the present invention is not claimed herein, as it forms the subject-matter of a co-pending divisional application Serial No. 361,642, filed February 27, 1920, by the present applicant.

Referring to the drawing, the apparatus there delineated for illustrative purposes shows a shoe 10, having an unfinished outsole 12, an attached heel 14 and top-lift 16 of final size and shape, clamped in position upon a support 20, the heel-seat 22 of the outsole 12 being both trimmed and randed by means of a rotary cutter 24 that is definitely positioned relatively to the heel-seat portion 22 during the trimming operation through the agency of a guide 26 that cooperatively engages the lateral surface of the definitely shaped heel 14 which serves as a pattern or templet.

The shoe 10 may be of any type of construction, having a rough, unfinished outsole secured thereto. The heel 14 is preferably treated and compressed to final size and

form in the manner set forth in the above mentioned copending application, and it is properly centered with respect to the shoe and attached to the heel-seat portion 22 of the outsole 12 in the ordinary manner, a top-lift 16, also of final size and form, being spanked on or otherwise suitably positioned.

The support 20 for holding the shoe during the trimming operation constitutes a plate that is rigidly associated with a supporting post 28 and is provided with edge clamps 30, an adjustable breast guide 32 for positioning the heel, and a clamping foot 34 that is disposed within the shoe and acts to firmly clamp the shoe to the support 20.

The rotary cutter 24 is provided with a hub 35 that is rotatably mounted upon a stud 36 which is carried by a supporting arm 38, and said cutter 24 is provided with an upper projecting cutting portion or lip 42 for beveling or cutting the randing 44 on the upper edge of the heel-seat portion 22 of the outsole 12, and also with a slightly inclined, main cutting portion 46 for trimming the edge thereof. The cutter 24 is of substantially the same width as that of the heel-seat portion 22 and is adapted to trim the outsole only. A pulley 48 is fixedly secured to the hub 35, and a belt 50 cooperates therewith to rotate the cutter 24 at high speed.

Beneath the cutter 24 and loosely mounted upon the hub 35 above the pulley 48, is the disk or guide 26, the periphery of which has the same inclination as that of the main cutting portion 46 of the cutter and extends in alignment therewith. The periphery of the guide 26 is adapted to engage the lateral surface of the definitely shaped and formed heel 14 at the edge of the heel seat and, thereby, to definitely position and guide the cutter 24 during the trimming operation, to the end that the heel-seat portion 22 of the outsole is trimmed and randed to the contour of the adjoining portion of the shaped heel as a pattern. In order to protect the upper 52 of the shoe 10 from being injured during the trimming operation, a disk or shield 54 is loosely mounted above the cutter 24 upon a screw 56 which is threaded into the end of the stud 36, and the edge of this shield projects into the heel-seat crease and serves as a barrier for the intended purpose.

During the trimming operation, relative bodily movement between the shoe 10 and the cutter 24 is effected in any suitable manner, it being within the contemplation of the invention that either or both the shoe and cutter be bodily rotated.

By reason of trimming and randing the heel-seat portion 22 of the outsole to the contour of the definitely shaped and formed heel as a pattern, it is evident that a corre-

spondingly definitely shaped outsole, heel-seat and randing will be insured. The heel-seat portion 22, heel 14 and top-lift 16 are subsequently lightly scoured and otherwise finished in accordance with well-known practice. Thus, regular, well-formed and substantially perfect completed heel ends are uniformly produced upon shoes that are operated upon in accordance with the method constituting the present invention.

Those skilled in the art will recognize that the apparatus illustrated is not the only apparatus that may be employed to practise the method herein disclosed and reference should be had to the appended claims which define the true scope of the invention.

Having thus described the novel method and one mode of practising it when employing its underlying principle, yet recognizing that some modifications and changes may be made without departing from its spirit and scope, what is claimed as new, is:

1. The method of making boots and shoes which comprises applying a definitely shaped heel of final form and size to the heel-seat of the outsole, and trimming the heel-seat of the outsole to the shaped heel.

2. The method of making boots and shoes which comprises positioning a definitely shaped heel of final form and size relatively to the heel-seat of the outsole, using the shaped heel as a guiding pattern to trim the outsole to a corresponding contour, and finishing the trimmed outsole and the definitely shaped heel at the same time.

3. The method of making boots and shoes which includes applying a definitely shaped heel of final size and form to the heel-seat of the outsole, and trimming and randing the heel-seat of the outsole to the shaped heel as a guide.

4. The step of making boots and shoes which consists in trimming the heel-seat of the outsole to the attached heel as a pattern.

5. The step of making boots and shoes which consists in randing the outsole to the attached heel as a pattern.

6. The method of shaping the heel-seats of outsoles to which a shaped heel has been applied which comprises trimming the heel-seat by a cut which does not extend into the adjoining heel, and utilizing the lateral surface of the heel body as a pattern to determine the contour of the trimming cut.

7. The method of shaping the heel-seats of outsoles to which a shaped heel has been applied which comprises trimming the heel-seat, and determining the contour of the trimming cut from the contour of the lateral surface of the heel at the edge of its heel-seat.

8. That improvement in methods of making shoes which consists in applying a previously shaped heel to an outsole having surplus material around the margin of its heel-

seat, and thereafter trimming said heel-seat by physical guidance of the edge of the heel-seat of the heel.

9. That step in making shoes which consists in trimming the edge of the heel-seat portion of an outsole by physical guidance of that portion of the lateral surface of a previously shaped heel which is contiguous to its heel-seat.

10. That step in making shoes which consists in simultaneously randing and trimming the edge of the heel-seat portion of an outsole by physical guidance of the edge of the heel-seat of a previously shaped heel.

15. That improvement in methods of making shoes which consists in clamping to each other an outsole and a heel, one of which has previously been shaped to determine the shape of the other, and thereafter trimming

20 said other by physical guidance of the con-

tiguous portion of the previously shaped one while maintaining them in clamped relation.

12. That improvement in methods of making shoes which comprises the step of removing waste stock from the periphery of the 25 heel-seat of an outsole to fit it to a heel, and gaging said removal, during the removing operation, by physical engagement and measurement of the edge of the heel-seat of a previously shaped heel.

30 13. That improvement in methods of making shoes which comprises the step of removing waste stock from the periphery of the heel-seat of an outsole to fit it to a heel, and determining the quantity of waste stock 35 to be removed by physical engagement and measurement of a previously shaped heel at the edge of the heel-seat thereof.

ERASTUS E. WINKLEY.
